SAFETY SHUTOFF VALVE MECHANISM

Thomas F. Van Denberg, Cleveland Heights, and
 John Selby, Euclid, Ohio, assignors to The
 Titan Valve and Manufacturing Company,
 Cleveland, Ohio, a corporation of Ohio

Application November 27, 1944, Serial No. 565,210

4 Claims. (Cl. 137—161)

1

This invention relates to safe control mechanism, such as is used for safeguarding the supply of fuel to a burner against the possibility of accident or injury as the result of extinguishment of a pilot light for the burner.

The invention has more particular relation to that class of safety devices in which a single control device, such as an electric switch, valve member, or the like is movable back and forth between idle or safe position and active or operating position, being releasably held in the operating position by maintaining means sensitive to variations in a condition, such as temperature, the maintaining means and control device being separately actuated to maintaining position and operating position, respectively, by the independent advance and retraction of a reset or cocking device.

One object of the invention is to provide improved control mechanism of the character described which reduces the number of necessary parts, simplifies the construction and secures more reliable and certain operation.

Another object is to provide improved mechanism of this kind in which all parts are arranged symmetrically about a common axis.

A further object is to provide control mechanism of this kind in which the casing or enclosing housing is in one piece and all working parts may be assembled on the bench in one unit for insertion into and attachment to the casing.

Still another object is to provide control mechanism of this kind embodying maintaining means in the form of cooperating magnet and armature members, one of which is attached to and is carried by a central stem upon which the cocking device is sleeved and slidable.

Finally, another object is to provide improved control mechanism of this kind in which all operating parts are assembled and supported upon a single stem or rod which forms one of the operating parts for the pilot valve and also serves as a guide for the movable main or shutoff valve.

Further objects of the invention in part are obvious and in part will appear more in detail hereinafter.

In the drawings, which represent one suitable embodiment of the invention,

Fig. 1 is a longitudinal sectional elevation, showing the parts in normal safe or idle position;

Fig. 2 is a similar view, showing the cocking device advanced, certain parts being omitted;

Fig. 3 is a similar view illustrating all parts in the active or operation position;

2

Fig. 4 is a cross section on the line 4—4, Fig. 1; and

Fig. 5 is a cross section on the line 5—5, Fig. 3.

While the invention may be applied for use in the operation of any kind of control devices, such as an electric switch, a valve, or the like, for convenience, and in no sense of limitation, it has been illustrated in a form including a valve for controlling the flow of fuel to a burner. The drawings illustrate valve mechanism including a hollow body or casing 10, which is a single integral member, in which is a safety shutoff valve 11 controlling the flow of fuel, such as gas, through an opening in a cross wall 12 dividing the cavity 15 within the hollow body into supply and discharge chambers 13, 14, the former communicating with a supply conduit 15 and the latter with a conduit 16 leading to the main burner 17. The shutoff valve 11 is slidably mounted upon a tube 18, being biased to move toward closed position by a compression spring 19. Tube 18 is sleeved upon an operating rod or stem 20 biased for outward movement, or to the left in Fig. 1 by a compression spring 21. The outer end of rod 20 is enclosed within a cap 22 attached to the tube 18, and the outer end of which cap forms a push button for depression by the operator's finger, to enable the cocking or resetting operation to be performed. Tube 18 is biased for outward movement, or to the left in Fig. 1, by the compression spring 23, which, at its inner end, abuts a washer 24 which confines in place a sealing device, such as the O ring 25 seated against an inwardly extending flange 26 of a thimble 27 screwed into the casing and to which all of the operating parts are connected.

The valve 11 is movable back and forth, by sliding movement on or with tube 18, between the normal safe or inactive position shown in Fig. 1 and the operating position shown in Fig. 3. When moved thereto, it may be maintained or held in the operating position by any suitable holding means, preferably operated by the cocking device. These holding means may be of any suitable form, such as a latch, or an electromagnet and armature energized by any suitable source of current, such as a thermocouple, but in the form shown the holding devices include the two members of a permanent magnet couple of the same general form and operating in the same general manner as those described and shown in a prior application for Safety valve mechanism, Serial No. 558,514, filed October 13, 1944, by Van Denberg and Selby, to which reference may be had if necessary or desirable. Either or both of

the members of the magnet couple may be movable. In the arrangement shown the armature member 28 is of washer form and firmly anchored or fixed in the body or casing. Its cooperating mating member is the permanent magnet 29 mounted upon and movable with the stem 20, which also carries a sealing ring 30 adapted to seat upon an annular flange on the inner end of the valve member 11 for preventing gas leakage through the working joints.

Upon the inner end of the stem 20 is threaded an enlarged extension 31, serving as a pilot valve, for which purpose it is provided with an annular groove 32 cooperating with a channel 33 communicating at one end with a pilot gas supply pipe 34 and at its opposite end with the tube of the pilot burner 35, located adjacent to the main burner 17. The stem extension 31 also serves as one of a pair of stop abutments controlling the production of the holding or maintaining effect. This it accomplishes by cooperation with an adjustable stop device sensitive to variations in an operation condition, such as variations in the temperature resulting from presence or absence of pilot flame. In the arrangement shown I provide a thermostatic device of tube and rod form, including a tube 36 and a rod 37, one of which, such as tube 36, may be made of material expansible by heat, such as brass or copper, and the other of which may be made of relatively non-expansible material, such as invar, or vice versa. To avoid the effects of variations in ambient temperature a push rod 38 is interposed between the inner end of the rod 37 and the stem extension 31, said push rod being made of material having the same coefficient of expansion under heat as that of the tube 36.

As will appear hereinafter, during the cocking operation, upon advance of tube 18 and stem 20 to the right in Fig. 1, the holding or maintaining devices are adjusted near to each other, but short of actual contact, ready for the production of maintaining effect, subject to the appropriate or necessary variation in temperature. This adjustment is produced without effect upon the shut-off valve 11 which remains in its safe or closed position. Its movement to operating position is initiated or produced by the return or retracting movement of the cocking parts after the holding effect is secured. For that purpose means is provided for making the cocking parts effective upon the valve for opening it during the latter portion of the cocking operation. To this end the stem 20 is provided with an annular external groove 39 having inclined end walls, and the inner cylindrical wall of valve 11 is provided with an annular recess 40, which annular recesses cooperate with one or more balls 41 (two, three or more of which may be used) each of which balls is confined in an opening 42 in the tube 18, as the result of which the balls move back and forth with the tube during its endwise movement and are also capable of inward or outward movement radially of the central axis, without escape from the tube opening.

The valve mechanism described operates as follows:

Fig. 1 illustrates all parts in the normal safe or inactive position. The pilot valve is closed, so that no gas flows to the pilot burner. The safety shutoff valve 11 is also closed so that no gas flows to the main burner. The pilot valve is held closed by spring 21, which is somewhat weaker than spring 19 which holds the shutoff valve closed. Sealing ring 30 prevents gas escape

7 through the operating joints. The balls 41 rest in the annular groove 39 in stem 20 and lie opposite a cylindrical portion of the opening in valve 11.

5 To set the parts into operation pressure is applied to the outer end of cap 22. The first effect is to take up any lost motion between the inner end of tube 18 and the shoulder on rod 20 at the sealing device 30. Then the rod 20 and tube 18 move together to the right to the position shown in Fig. 2, where the end of stem extension 31 has engaged the end of the push rod 38, with all lost motion taken up. Annular groove 32 is now opposite the pilot channel 33 so that gas flows to the pilot burner. However, as in the prior application before referred to, the two members of the permanent magnet couple are not yet in actual contact with each other, being separated by a space of the order of .020 of an inch. Therefore, if the cocking device is released the parts return to their original positions, shutting off the pilot gas supply. However, if the pilot burner is ignited the flame jets from its burner ports play upon the thermostatic device and expand the tube thereof, in the form shown, so that the thermostatic rod 37 and push rod 38 move to the right until the permanent magnet reaches actual contact with the armature, with a holding or maintaining effect. The inclined wall at the left-hand end of 10 the annular groove 39 in stem 20 is at the right of the inclined wall at the end of the annular groove 40 in the valve 11. Therefore, when the finger is removed from cap 22, tube 18 moves to the left under the compression of spring 23, causing the balls 41 to move radially outwardly and enter the annular groove 40 and ride along the outer surface of rod 20. Retracting movement of tube 18 also moves valve 11 to the left to the open or active operating position shown in Fig. 3. 15 This opens communication from the supply to the discharge chamber and gas flows to the main burner where it is ignited by the pilot flame.

20 The parts remain in the active or operating position until the pilot flame goes out. When this occurs the thermostatic device cools down, and tube 36 contracts and moves the push rod 38 to the left, thus applying pressure to the stem extension 31 and to the permanent magnet which it supports, to an extent sufficient to bodily move the permanent magnet out of engaging contact with its mating armature member. Thereupon the stem 20 is retracted by the expanding effect of its spring 21, causing it to return to its original position shown in Fig. 1. Such motion brings the 25 channel 39 opposite to the balls 41, which enter said channel and therefore are disengaged or freed from the valve member 11, releasing the same and permitting it promptly to advance to its safe or closed position under the influence of its spring 19. This brings all parts to their original safe positions ready for another cycle of operations.

30 It will be observed that in this mechanism the valve housing or body is a single member or casting, without any cap or joint, but cored out to provide the necessary interior chambers. All working parts are attached to and supported by the central stem 20 and the thimble 27 in which it is mounted, so that the working parts conveniently may be made and assembled on the bench with all parts exposed to view and convenient for assembly and adjustment. Also, all parts are symmetrically disposed around the axis of stem 20. Advance of the cocking device brings the 35 maintaining or holding devices into close rela-

tion, but the actual production of a holding effect is sensitive to the necessary variation in temperature produced by ignition of the pilot burner. The production of the holding effect is independent of valve movement or operation. Retraction of the cocking device opens the valve without effect upon the holding devices which, thereafter, are sensitive only to the appropriate variation in the controlling condition, such as temperature.

The mechanism is of simple form, can be made and assembled at low cost, and is highly satisfactory in operation.

What we claim is:

1. Control mechanism of the character described, comprising a hollow body provided with supply and discharge chambers communicating through an opening in a cross wall, a valve controlling flow through said opening, and a thimble secured in an opening of the body, a stem movably supported in said thimble, a valve slidable back and forth along said stem, a holding device advanced by and with said stem to holding position when the stem is moved in one direction, a cocking device carried by said thimble and slideable on the stem for so moving said stem, and operating connections between said valve and device for opening the valve when the device is moved in the opposite direction.

2. Control mechanism of the character described, comprising a control device movable back and forth between safe and operating positions, a stem along which said device is movable, holding members relatively movable longitudinally of the stem into and out of holding relation, one of which is secured to said stem for operative movement thereby, a tubular cocking device slideable on said stem, and means arranged upon movement of said cocking device in one direction to couple it to said stem for movement thereof and upon movement in the opposite direction to couple it to said control device for movement thereof.

3. Control mechanism of the character described, comprising a control device movable back and forth between safe and operating positions, a stem along which said device is movable, holding members relatively movable into and out of holding relation, one of which is operated by said

5 10 15 20 25 30 35 40 45 50 55 60 65 70 75 80 85 90 95 100

stem, a tubular cocking device slideable on said stem, means arranged upon movement of said cocking device in one direction to couple it to said stem for movement thereof and upon movement in the opposite direction to couple it to said control device for movement thereof, stop means for limiting relative approach of said holding members to a position in which they are close but out of contact, and thermostatic means controlling said stop means for permitting actual contact of said holding members.

4. Control mechanism of the character described, comprising a control device movable back and forth between safe and operating positions, a stem along which said device is movable, holding members relatively movable into and out of holding relation, one of which is operated by said stem, a tubular cocking device slideable on said stem, means arranged upon movement of said cocking device in one direction to couple it to said stem for movement thereof and upon movement in the opposite direction to couple it to said control device for movement thereof, stop means for limiting relative approach of said holding members to a position in which they are close but out of contact, and thermostatic means controlling said stop means for permitting actual contact of said holding members and for separating them when in contact to release the control device.
